SAFETY CURRENT SUPPLY FOR PHOTO-ELECTRIC LIGHT SOURCES

Eliot A. Cranch, Denver, Colo.

Application April 8, 1947, Serial No. 740,238

1 Claim. (Cl. 250—41.5)

1

This invention relates to a safety photo-electric cell circuit. Photo-electric cells are used for starting or operating machines of various kinds in response to the breaking of a light beam by a work piece being placed in the machine. In the usual photo-electric circuit for this use a relay or relays are employed for closing a main circuit. The relay is energized from a control circuit in which the current flow increases as the light supply to a photo-electric cell decreases. The lamp supplying the light beam to the photo-electric cell is energized independently of the control circuit. Therefore, should the current supply to the lamp fail, or should the lamp itself burn out, the control circuit will be energized to operate the relay, closing the main circuit. This, of course, is very dangerous, for it will start the machine being controlled at unpredictable times, and keep it in operation until manually stopped by the attendant.

The principal object of this invention is to provide a circuit in which the lamp will be placed in series with the control circuit so that, should the light source fail for any reason, the control circuit will be de-energized to open the main circuit relay and prevent starting of the machine until repairs or replacements have been made.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

The invention involves but little change in the conventional circuit and is best described and understood by reference and comparison with the conventional standard circuit. For this purpose, such a conventional circuit is illustrated in Fig. 1 of the drawing, and the same circuit changed to adapt it to the objects of this invention is illustrated in Fig. 2.

The conventional elements of a photo-electric control circuit are indicated diagrammatically on the drawing and designated by numeral as follows: main circuit 10, to be controlled by the photo-electric circuit; relay 11, for closing main circuit 10; photo-electric cell 12; lamp 13, for illuminating a photo-electric cell; reflector 14; condensing lenses 15; light beam 16; electrolytic tube 17; balancing resistors 18 and 19; grid leak

2

resistor 20; half-wave rectifying tube 21; and alternating current supply leads for control circuit 22.

The circuit of Fig. 1 is conventional. The current for operating the lamp 13 is supplied from an outside source through an independent lamp circuit 23. The control circuit is supplied with half-wave rectified current through the rectifier tube 24, which is connected through the medium of a rectifier conductor 25 and a relay conductor 26 with the relay 11. The tube 21 is supplied from one of the alternating current leads 22. The other lead feeds the grid of the tube 17 through a conductor 24, the resistor 18, and a cathode conductor 20. The plate current from the tube 17 is conducted to the relay 11 through a plate conductor 26. The circuit is bridged by a shunt conductor in series with the balance resistor 19. The resistor 19 is of a value which will impress a proper bias on the cathode of the tube 17.

The flow of the bias current is controlled by the grid of the tube 17, which is energized from the photo-electric cell 12 through a grid conductor 29. The grid 29 and the cathode 28 are of the same polarity so that when the photo-electric cell 12 is energizing the grid of the tube 17, no current will flow through the relay 11. Should the light beam 16, however, be interrupted, no current will flow to the grid, so that the full bias of the tube 17 will flow to the plate conductor 26, causing the relay 11 to close the main circuit 10.

As thus far described, and as illustrated in Fig. 1, the circuit is the conventional one. It was thought best to first describe and illustrate the conventional circuit in order that the changes and additions thereto would be more readily understandable.

It can be readily seen that should the lamp circuit 23 fail, or should the lamp 13 burn out, the relay 11 will be energized, closing the main circuit 10. This closure may occur at a time to do great damage if the circuit is being used for machine control, or if used for pump control the pump will operate until stopped manually.

This invention is designed to cause the relay 11 to remain open should any failure occur in the light source. This is accomplished by very slight changes in the conventional circuit of Fig. 1.

The outside lamp circuit 23 and the relay conductor 26 are eliminated and the lamp 13 is placed in series, by means of a lamp conductor

30 and a lamp-relay conductor 34, between the relay 11 and the rectifying tube 21, so that all current flowing through the relay 11 must also flow through the lamp 13. The circuit for this relay current may be traced as follows: from one of the supply leads 22 through the conductor 24, the resistor 18, the cathode conductor 28, the plate conductor 26, the relay 11, thence through the conductor 34, the lamp 13, and the rectifier conductor 27, thence back to the other supply lead 22. This circuit and this current serve no function in illuminating the lamp 13.

The current for activating the filament of the lamp 13 is obtained by bridging a condenser circuit 32 between one of the supply leads 22 and the lamp-relay conductor 34. The latter circuit is broken by a condenser 33 which allows the alternating current from the leads 22 to pass, but prevents the half-wave current from the relay 11 from being shorted across the lamp 13.

The lamp energizing circuit may be traced as follows: from one of the alternating current supply leads 22 through the conductors 24 and 25 and resistors 18 and 19 to the conductor 30, thence through the lamp 13, the lamp-relay conductor 34, the bridging conductor 32 and the condenser 33 to the opposite supply lead 22.

It can be seen from the above that the photoelectric control circuit will operate similarly to the conventional one of Fig. 1. It will also be seen that the lamp 13 will remain illuminated as long as current is supplied through the leads 22. Should the lamp 13 burn out, however, the half-wave relay circuit is broken at this point, for current cannot flow from the relay 11 to the rectifier tube 21. Therefore, the relay cannot operate and the main circuit 10 will remain open until repairs or replacements are made.

While a specific form of the improvement has been described and illustrated herein, it is desired to be understood that the same may be varied, within the scope of the appended claim, without departing from the spirit of the invention.

Having thus described the invention, what is claimed and desired secured by Letters Patent is:

- 10 A photo-electric cell control circuit comprising: a rectifier; a grid-controlled electronic tube; a photo-electric cell supplying current to the grid of said tube; a lamp supplying a light beam to said photo-electric cell; a relay; a pair of 15 alternating current supply leads, one of said leads being connected to the cathodes of said photo-electric tube and said electronic tube, the second supply lead being connected successively in series through said rectifier, said lamp, and said relay to the plate of said tube; and a bridging conductor extending from the second supply lead to a connection between said lamp and said relay to supply alternating current to energize said lamp, said bridging conductor including a condenser to prevent short-circuiting of the rectified current flowing through said lamp.
